INVENTOR

E. E. Buttles

UNITED STATES PATENT OFFICE.

ELWIN E. BUTTLES, OF BLACKCREEK, WISCONSIN.

IGNITER.

No. 899,950.

Specification of Letters Patent. Patented Sept. 29, 1908.

Application filed January 8, 1908. Serial No. 409,881.

To all whom it may concern:

Be it known that I, ELWIN E. BUTTLES, a citizen of the United States, residing at Blackcreek, in the county of Outagamie and State of Wisconsin, have invented certain new and useful Improvements in Igniters; and I do hereby declare the following to be a full, clear, and exact description of the invention, such as will enable others skilled in the art to which it appertains to make and use the same.

My invention relates to new and useful improvements in igniters and more particularly to that class adapted to be used for striking matches and my object is to provide a device of this class which may be secured to the inside of a garment so that the same will not be exposed to view.

A further object is to provide means for readily securing the igniter to the garment.

A still further object is to provide means for holding the adjacent portions of the garment away from the striking portion of the igniter.

Other objects and advantages will be hereinafter referred to and more particularly pointed out in the claims.

In the accompanying drawings which are made a part of this application, Figure 1 is a perspective view showing my improved igniter applied to use. Fig. 2 is a plan view thereof, removed from the garment. Fig. 3 is a similar view of a slightly modified form of device. Fig. 4 is a sectional view as seen on line 4—4 Fig. 2. Fig. 5 is a sectional view as seen on line 5—5 Fig. 3 showing the igniter attached to a garment, and, Fig. 6 is a plan view of a slightly different form of igniter.

In providing an igniter of this class and securing the same to a part of the garment I obviate the necessity of striking the match directly on the garment which would result in spoiling the garment by leaving marks thereon, and it is my desire to construct a device that may be secured to the under side of the garment so that when the device is not in use the same will be removed from sight and to this end I provide a body 1 which is preferably constructed from cheap metal, to the rear face of which is secured a retaining pin 2, said pin being preferably constructed in the form of a safety pin and having one of its bars secured in any preferred manner as by soldering, to the rear face of the body 1 so that when the opposite bar of the pin is

inserted through a portion of the garment, the body will be securely held in place thereon. It is further to be observed that the retaining pin is so secured to the rear face of the body 1 as to cause said pin to lie closely thereto, so that the engaging portion of the pin may be moved in a plane approximately parallel with the plane of the body.

In order to cause the head of the match to ignite when drawn across the body 1, I provide a plurality of serrations 4 on the outer surface of the body 1 by striking up portions of the surface of the body so that said surface will be roughened which will result in positively igniting the match when the head thereof is drawn across the serrations.

Immediately surrounding the serrated portion of the body surface is a bead 4^a which is formed by curving outwardly the periphery of the body and it will be seen that the garments will be engaged by the bead and held out of contact with the serrations on the body. It will further be seen that by directing the free edge of the bead a sufficient distance beyond the rear face of the body that a slight cavity will be formed thereby fully protecting the retaining pin when the igniter is not in use. The projecting edge of the bead will also bind against the garment and when the pin is secured therethrough thus forming a rigid bearing for the igniter.

In Figs. 3 and 5, I have dispensed with the retaining pin 2 and in place thereof I have provided the periphery of the bead 4^a with a plurality of pointed tongues 5 which are directed through the inner lining of the garment and bent upon themselves to secure the body to the garment, the manner of applying the same being clearly shown in Fig. 5 of the drawing.

In Fig. 1 of the drawing, I have shown the device as applied to use and in this instance I have secured the body to the inner face of the vest and when it is desired to strike a match, the lower edge of the vest is lifted which will result in exposing the serrated portions of the body and by drawing the head of the match there across, said head will be ignited and when this result is accomplished, by returning the upturned portion of the vest to its normal position, the igniter will be entirely removed from view.

In Fig. 6 of the drawing I have shown a slightly different form of device in that the

serrations in the surface of the body are dispensed with and the outer edges thereof provided with retaining strips 6 which are adapted to extend over the edges of and secure to the body a section of sand paper or the like 7, the roughened surface of the section of paper serving the same purpose as the serrations, and the strips 6 serving the same purpose as the bead 4^a.

10 It will now be seen that I have provided a very cheap and economical device for igniting a match head and one that can be attached to the garment and disposed out of view when not in use.

15 What I claim is:

An igniter of the class described comprising a body having a roughened surface and

a bow pin secured to said body, one of the bars of the pin being secured approximately centrally of the under surface of the body, 20 the second bar of the pin being movable in a plane approximately parallel with the plane of the body the edge portions of the body being bent to form a bead, the edge of the bead projecting beyond the outer surface 25 of the bow pin.

In testimony whereof I have signed my name to this specification in the presence of two subscribing witnesses.

ELWIN E. BUTTLES.
